UNITED STATES PATENT OFFICE.

FRANK SIMONS, OF BUFFALO, NEW YORK.

SUPPORT FOR TELEPHONE-RECEIVERS.

No. 895,695.

Specification of Letters Patent.

Patented Aug. 11, 1908.

Application filed October 1, 1906. Serial No. 336,941.

To all whom it may concern:

Be it known that I, FRANK SIMONS, a citizen of the United States, residing at Buffalo, in the county of Erie and State of New York, have invented certain new and useful Improvements in Supports for Telephone-receivers, of which the following is a specification.

This invention relates to a support for telephone-receivers, and its primary object is the production of a simple, durable, and efficient support whereby the receiver may be used and held in proper position with relation to the ear of the user and the mouth of the transmitter, without being held by the user, so that the hands of the user are free to take written notes of the messages received.

Another object is the production of a support of the type mentioned which may be swung out of the way, and which embodies in its construction, means to maintain the support in proper position with relation to the mouth of the transmitter when swung outward.

The invention consists in the novel construction of the support and in the combination and arrangement of parts to be hereinafter described and particularly pointed out in the appended claims.

In the drawings,—Figure 1 is a perspective view of my improved support applied to the arm of a transmitter and supporting a receiver, shown in dotted lines. Fig. 2 is a plan view of the support affixed to the arm of the transmitter; the support being shown in dotted lines as swung inward into a position of disuse. Fig. 3 is an enlarged side elevation of the clamp on which the supporting-member is pivotally held. Fig. 4 is an enlarged section taken on line 4—4, Fig. 2. Fig. 5 is an enlarged section taken on line 5—5, Fig. 2.

Referring to the drawings in detail, like numerals of reference refer to like parts in the several figures.

The numeral 6 designates a telephone-transmitter and 7 a telephone-receiver supported on my improved device. The support comprises a clamp 8 adapted to be secured to the arm of the transmitter, and a supporting-member 9 pivotally attached to said clamp. The clamp is preferably cast and of U-shape to straddle the arm of the transmitter; it having formed integrally therewith on one side, a lug or extension 10

having a vertical opening 11 and a notch 12 at its upper end extending from said opening to the outer face of the lug. Said clamp is provided with a screw-hole 13 on its opposite side through which is passed a binding-screw 14 with its end impinging against the side of the transmitter arm. This binding screw renders the clamp suitable for use on all sizes of transmitter-arms; the screw 15 being adjustable, serves to draw the clamp firmly against one side of the said arm. The lower ends of the clamp extend beneath the arm of the transmitter and have alined openings 15, one of which is threaded 60 to receive the threaded end of a clamping-screw 16 passed through the other opening. When the clamping-screw is tightened; the clamp is held positively against movement, particularly since the binding screw 14 acts 65 as a fulcrum from which the arm through which said screw passes is drawn inward when the clamping-screw is tightened.

The supporting-member is constructed of a single piece of wire of suitable diameter 80 and strength, and comprises an outstanding intermediate portion 17 bent laterally at its inner end, as at 18; a depending retainer-portion 19 at the inner end of the supporting-member; and a receiver-support 20 at the 85 outer end of said member. The intermediate portion is given any angle or curve necessary to bring the receiver-support in proper position with reference to the mouth of the transmitter.

At the outer end of the intermediate portion 17, the wire is bent into substantially U-shape, as at 21, thence laterally, as at 22, and finally terminating in a curved portion 23 also of U-shape and in line with the U-shaped portion 21. The laterally disposed portion 22 serves as a connection between the U-shaped portions 21 and 23, in which the telephone-receiver is placed, as shown in dotted lines, Fig. 1. The depending retainer-portion 19 is inserted into the opening 11 to permit the supporting-member to be swung inward into a position of disuse, or outward into proper position with respect to the mouth of the transmitter. When in the latter position, the inner end or laterally bent portion 18 of the intermediate portion fits into the notch 12 of lug 10, and prevents swinging movement of the supporting-member. It is therefore necessary, in order to 105 swing the supporting-member into a position of disuse, that it be slightly elevated so that

the top of lug 10 is cleared by the intermediate portion of said member.

Having thus described my invention, what I claim is,—

- 5 A support for telephone-receivers, comprising a U-shaped clamp adapted to fit onto the arm of a telephone transmitter and having a laterally extending lug provided with a vertical opening and a notch in the upper 10 end of said lug, said clamp having its ends extending beneath said arm and provided with alined apertures, a binding-screw passing through one side of said clamp and impacting against said arm, a clamping-screw 15 passing through one of said alined apertures and threaded into the other of said apertures, a supporting - member formed of a single

piece of wire and having an outstanding intermediate portion, a depending retainer portion entering the opening in the lug of 20 said clamp, and a receiver support formed at the outer end of said intermediate portion by curving the wire into two alined U-shaped supports connected by a single laterally disposed portion of the wire, the inner end of said 25 intermediate portion fitting into the notch on said lug.

In testimony whereof, I have affixed my signature in the presence of two subscribing witnesses.

FRANK SIMONS.
